United States Patent Office

Des. 185,106
Patented May 5, 1959

185,106

BATTERY RACK

Richard H. Van Den Berg, Milwaukee, Wis., assignor to
U-Test-M Mfg. Co., Inc., Milwaukee, Wis., a corpora-
tion of Wisconsin

Application December 2, 1958, Serial No. 53,628

Term of patent 14 years

(Cl. D80—9)

Fig. 1 is a front elevational view of a battery rack showing the new design;

Fig. 2 is a top plan view of the battery rack; and

Fig. 3 is a side elevational view of the battery rack.

I claim:

The ornamental design for a battery rack, as shown.
